UNITED STATES PATENT OFFICE.

SIGMUND BERGMANN, OF NEW YORK, N. Y.

COMBINED GAS AND ELECTRIC-LIGHT FIXTURE.

SPECIFICATION forming part of Letters Patent No. 375,117, dated December 20, 1887.

Application filed October 31, 1884. Serial No. 146,888. (No model.)

To all whom it may concern:

Be it known that I, SIGMUND BERGMANN, of New York, in the county and State of New York, have invented a certain new and useful Improvement in Combined Gas and Electric-Light Fixtures, of which the following is a specification.

The object of my invention is to produce a more practical and efficient construction of swinging brackets for use with either gas or the incandescent electric light than has heretofore been in use. In accomplishing this object I employ two rigid jointed hollow arms—one for conveying gas, the other inclosing flexible electrical conductors extending through it from end to end. These two parts are connected and pivoted together, so as to swing simultaneously. One terminates in a gas tip or burner, the other in a socket for holding an incandescent electric lamp.

Since it is necessary to have a tight connection between the relatively swinging parts of the gas-bracket in order to convey the gas, and since it is practically impossible in making the parts to cause them to fit perfectly and without any inaccuracy, I make the connection between the swinging parts of the electric-light arm a loose one, so that the gas and electric-light arms may swing truly together in spite of such necessary inaccuracies of construction, for if both joints were rigid and the parts were not accurately fitted one part or another would be likely to be broken or bent in swinging the fixture.

In the accompanying drawings, Figure 1 is a view in elevation of a single-swing bracket, and Fig. 2 a view of a double-swing bracket, each embodying my invention; and Fig. 3 is an enlarged sectional view of the inner end 4c portion of a bracket.

The bracket consists of two hollow arms, *a*, Fig. 1, or *a' a'*, Fig. 2, and *b b'*, Fig. 1, or *b b' b'*, Fig. 2, both jointed at *c c'*, as will be presently explained. The jointed arm *a* or *a' a'* is a gas-conveying arm and terminates in the gas-burner *d*. The jointed arm *b b'* or *b b' b'* incloses two flexible separately-insulated electrical conductors, *e e*, which pass through the joints of the arm and enter the socket *f*, attached to the end of the tube, where they are connected, as usual, to terminals, with which

the terminals of the incandescent electric lamp *g* make contact when the lamp is screwed into the socket.

The gas pipe *h*, which carries the bracket, 55 is preferably provided with an insulating joint, *i*, of the usual construction. Upon the end of the pipe which protrudes beyond the ornamental cap *k* is screwed the block *l*, which has the gasway *m* through it, and has at its 60 outer end the aperture *n*, in which the gas-plug *o* is inserted, being held by the screw *p* and washer *r*, so as to turn in the aperture. From the block *s*, below the gas-plug, extends the first arm, *a*, of the jointed gas-tube. 65

The turning block *s* has the screw *t* entering its lower end, which screw carries the two-part shell *u u'*, the upper half, *u*, of which is stationary, the screw turning through it, while the lower half, *u'*, turns with the screw. In 70 an aperture in *u* is inserted the outer end of inclosing-tube *b*, whose inner end enters the cap *k*, where the protruding conductors are suitably connected with the house-wires. From *u'* extends the tube *b'*, and the flexible 75 conductors *e e* extend continuously through the joint, as shown. The upper portion of screw *t* is white-leaded to make a gas-tight joint, or the gasway need not extend through to the screw-hole. The meeting surfaces of *u* 80 and *u'* are flat surfaces, the connection being, therefore, a loose one, such as to permit a slight oscillation between these parts to compensate for inaccuracies in construction, which might prevent the two arms from turning evenly. 85 The arms *a* and *b'* are swung simultaneously, turning on the same center, the block *s*, screw *t*, and lower half, *u'*, of the cap being turned, while *u* is stationary. A similar joint to that just described is made at *c'* in the double 90 bracket, Fig. 2.

The inner end of the wire-inclosing arm is preferably supported by the downwardly-extending support *v*, through the lower end of which the tube passes, being held by set-screw 95 *w*, whereby the part *b* is held rigidly stationary. The two arms may be further connected together by suitable clamps, *y*, each of which is made in two parts united by a screw, *z*.

It will be seen that by the above construction I have produced a simple and cheap fixture, and one whose parts are readily sepa-

rated and replaced when necessary, in which the conductors are inclosed and protected, while not exposed to contact with the gas.

What I claim is—

- 5 1. In a combined gas and electric-light fixture, the combination, with the turning block at the joint of a swinging gas-arm, of the screw extending below the same, the two-part shell carried by said screw, and the two hollow electric-light arms, one entering each half of said shell, substantially as set forth.
- 10 2. In a combined gas and electric-light fixture, the combination of a jointed gas-arm having tight gas-conveying joints and another jointed arm inclosing electrical conductors, the joints of the latter arm being loosely connected, and the two arms being mechanically

connected together, so as to swing on the same centers, substantially as set forth.

- 15 3. In a combined gas and electric-light fixture, the combination of the stationary portion of the gas-arm and the stationary portion of the electric-light arm, connected together by a rigid support, the swinging gas-arm connected by a tight joint with the stationary part, and the swinging electric-light arm connected with the stationary portion by a loose joint, substantially as set forth.

This specification signed and witnessed this 27th day of October, 1884.

SIGMUND BERGMANN.
